a corporation of Illinois

Application April 8, 1943, Serial No. 482,229

6 Claims. (Cl. 101—409)

The present invention relates to printing presses, and more particularly to protective and covering means for certain portions of printing presses.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawing, referred to herein and constituting a part hereof, illustrates one embodiment of the invention, and together with the description, serves to explain the principles of the invention.

Of the drawing:

Fig. 1 is a transverse cross sectional view of certain portions of a printing press folding mechanism embodying the present invention;

Fig. 2 is a longitudinal cross sectional view taken along line 2—2 of Fig. 1; and

Fig. 3 is a transverse cross-sectional view taken along line 3—3 of Fig. 2.

It is an object of the present invention to provide protective and covering means for certain mechanisms of a printing press. Another object is to promote the accurate and faultless operation of certain mechanisms of a printing press having cam actuating means by providing a substantially dust tight enclosure about such means for the exclusion of dust, bits of paper and other debris from the mechanism. The invention provides a protective covering about the cam mechanism of certain parts of a printing press and is particularly adapted to mechanism in which a portion of the cam track is removable.

With these and other objects in view there is provided in a typical and illustrative embodiment of the invention a printing press folder having a rotatable collecting cylinder for the collection of printed products. As embodied, the collecting cylinder is provided with a plurality of impaling pins mounted on a shaft capable of rotary movement within the cylindrical surface of the cylinder so that the pins may be projected out of the surface of the cylinder to engage a product thereon, and retracted within the cylinder in a position to release or not to engage the product. The shaft at one end of the collecting cylinder has a cam follower eccentrically mounted to be received in a stationary cam track

adjacent the end of the folder, whereby the pins may be actuated at desired times by the configuration of the track.

The cam track is adapted to actuate the impaling pins for every product received on the cylinder, or to actuate the pins only for every other product when the cylinder is to be run collect. As embodied a segment of the cam track is removable from the path of the cam follower, 10 and this segment is pivotally mounted for actuation from a cam track on a cylinder adjacent to the collecting cylinder. The removable segment of the cam track may be removed by action of the adjacent cylinder cam track so that the impaling pins are actuated only for alternate products of the folder, or the removable segment may be disconnected from actuation by the adjacent cam track and fixed in position to actuate the impaling pins for every product, 20 whereby the collecting cylinder is run collect or straight run, respectively.

The stationary collecting cylinder cam track member is provided with an integral annular portion having a finished radially extending surface, and this extends to a position closely adjacent a radially extending annular surface of a substantially cylindrical cover which is secured to the end of the collecting cylinder, the two members serving to enclose the cam track and follower mechanism in a substantially dust tight protective enclosure. An arcuate plate is secured to the outer side of the removable segment of the cam track member and is adapted to close off the space between the segment and stationary part of the track member when the removable segment is pivoted, in order to retain the protective enclosure about the cam mechanism. Extensions are provided on the stationary member of the cam track adjacent the pivotally mounted segment to cover off the gap through the width of the members when the removable segment is pivoted out of position, thus preventing entrance of dust and debris.

It will be understood that the foregoing general description and the following detailed description as well are exemplary and explanatory of the invention but are not restrictive thereof.

Referring now in detail to the illustrative embodiment of the invention as shown by way of example in the accompanying drawing, a printing press folder mechanism of the magazine type is provided with a collecting cylinder 10 and male and female cutting cylinders 11 and 12 respectively (details of the last two cylinders not being necessary for an understanding of the present

invention and, therefore, not being shown). As shown in Fig. 2, the collecting cylinder 10 is rotatably mounted by a shaft 13 which is mounted in the folder frame 14. A shaft 20 is mounted in the ends of collecting cylinder 10 for rotary movement by means of bearings 21 and carries a plurality of impaling pins 22 along its length. The impaling pins 22 have curved shanks and are adapted to have their points thrust beyond the surface of cylinder 10 by rotary movement of shaft 20 to engage printed products on the cylinder, and to be withdrawn again within the outline of the cylinder.

At one end of cylinder 10 the shaft 20 has an eccentric arm 25 to carry a cam following roller 26 in order to rotate the shaft and actuate the impaling pins from a cam track. As embodied, the cam mechanism comprises a cylindrical portion 27 securely fastened to the folder frame 14 by means of a plurality of tap bolts 28, and an outwardly radially extending annular cam track member 30, having a depressed track of desired configuration on its inner face to receive follower 26. The cam track member 30 has a finished surface 31 at its inner face, and positioned closely adjacent this surface is the finished surface 32 of a substantially cylindrical cover 33. These surfaces are positioned as closely adjacent as may be practically possible without touching. The cover 33 is secured to the end of collecting cylinder 10 by means of tap bolts 35 for rotation therewith, and encloses and protects from press room dust and debris the cam track and follower mechanism.

A segment 36 of the cam track 30 is adapted to be moved out of cam track registering position so that it will not actuate the impaling pins 22. As embodied, the removable segment 36 is integral with a lever 37 which is pivotally mounted on a shaft 38 suitably secured to the folder frame or other stationary part of the printing press. The lever 37 is removably secured to an extension 34 by means of a bolt 39 which passes through a pair of connection members 40, one integral with lever 37 and the other with the lever's extension 34. The extension 34 has a cam follower 41 at its end to be received in a cam track 42 at the end of the male cutting cylinder 11, whereby the removable cam track segment 36 may be actuated from cam track 42.

When the printing press folder is operating to collect the configuration of cam track 42 is such that it will remove segment 36 for every other product received on collecting cylinder 10, so that impaling pins 22 will be actuated for and engage only alternate products, from cam track member 30. In order to preserve the protective enclosure about the collecting cylinder cam mechanism when the segment 36 is in removed position, an arcuate plate 45 is secured to the outer face of removable segment 36 of cam track member 30 by means of tap screws 46. The inwardly radially extending width of plate 45 is sufficient to cover the radial space between removable segment 36 and cam track member 30 when the former is in removed position.

In order further to preserve the cam mechanism enclosure during collect operation of cylinder 10, the cam track member 30 has an extension or lip 47 on its outer periphery. The inner surface 48 of extension 47 and the adjacent edge 49 of removable segment 36 are machined in curved surfaces on a radius about the pivot point of lever 37 on shaft 38, so that extremely close adjacency may be maintained throughout move-

ment of segment 36. The axial space between segment 36 and member 30 is thus closed when the segment is out of cam track registering position.

Another lip or extension 60 of stationary cam track member 30 is provided adjacent the other end of segment 36, and the radially outward portion 61 of this extension is likewise finished in a curved surface on a radius about the pivot point of lever 37. Thus substantially no gap will be left at this location between the cam track member 30 and removable segment 36 when the latter is out of cam track registering position.

When cylinder 10 is to be operated straight run, and every product of the printing press engaged by impaling pins 22, the lever 37 may be disengaged from its extension 38 by removing bolt 39. Lever 37 may then be secured by means of tap bolt 50 to an extending portion 51 of folder frame 14. When the lever 37 is so positioned and secured the removable segment 36 will be in place as a part of cam track member 30 to actuate impaling pins 22.

The invention in its broader aspects is not limited to the specific mechanisms shown and described but departures may be made therefrom within the scope of the accompanying claims without departing from the principles of the invention and without sacrificing its chief advantages.

What I claim is:

1. In a printing press having a rotatably mounted cylinder member carrying paper gripper mechanism and cam mechanism at the end of the cylinder member for actuating the gripper mechanism and including a cam track member having a removable cam track segment movable into and out of registration with said cam track member, the combination of a cover element secured to one of said members extending closely adjacent to the other of said members enclosing the cam mechanism, and other cover means at the outer side of the cam track member for closing the gap between the removable cam track segment and the cam track member when the cam track segment is out of registering position.

2. In a printing press, having a rotatably mounted cylinder having movable sheet taking means, and cam mechanism at the end of the cylinder for moving the sheet taking means including a cam follower connected to the sheet taking means and a cam track member having a cam track to receive said cam follower, said cam track member having a removable segment movable into and out of cam track registering position, the combination of a cover secured to the cylinder and extending closely adjacent to the cam track member enclosing the cam follower and cam track, and means for closing the space between the cam track member and the removable segment when the segment is out of cam track registering position.

3. In a printing press, having, a rotatably mounted cylinder having movable sheet taking means, cam mechanism at the end of the cylinder for moving the sheet taking means including a cam follower connected to the sheet taking means and a cam track member having a cam track to receive said cam track follower, and an annular cover secured to the cylinder and extending closely adjacent to the cam track member enclosing the cam track and cam follower, said cam track member having a removable segment movable into and out of cam track regis-

tering position, the combination of a substantially radially disposed cover member secured to the segment to close the radial space between the segment and the cam track member when the segment is out of cam track registering position, and means for closing the axial space between the segment and the cam track member when the segment is out of registering position.

4. In a printing press, having, a rotatably mounted cylinder having movable sheet taking means, cam mechanism at the end of the cylinder for moving the sheet taking means including a cam follower connected to the sheet taking means and a cam track member having a cam track to receive said cam track follower, said cam track member having an annular finished portion on its side toward the cylinder, and a removable segment movable into and out of cam track registering position, the combination of an annular cover secured to the cylinder extending toward the cam track member and having a finished annular end closely adjacent to said finished portion whereby the cam track and cam track follower are enclosed in a substantially dust tight enclosure, an arcuate substantially radially disposed cover member secured to the outer face of the segment to close the radial space between the segment and the cam track member when the segment is out of cam track registering position, and means for closing the axial space between the segment and member when the segment is out of registering position including an extension secured to said

member having an edge extending along the path of movement of said segment.

5. In a printing press, having a rotatable cylinder with movable sheet taking means, cam mechanism at the end of the cylinder for moving the sheet taking means including a cam follower connected to said means and a cam track member having a cam track to receive said cam follower, said cam track member having a removable segment movable into and out of cam track registering position, the combination of an annular cover between the cylinder and cam track member substantially completely enclosing the cam track and cam track follower, and means for enclosing the space between the removable segment and cam track member when the segment is out of cam track registering position.

6. In a printing press, having a rotatable cylinder with movable sheet taking means, cam mechanism at the end of the cylinder for moving the sheet taking means including a stationary cam member having a removable segment movable for registering and removed positions, the combination of means between the cylinder and the cam member substantially completely enclosing the cam mechanism when the segment is in registering position, and other means between the segment and the cam member for closing the gaps therebetween when the segment is in removed position.

EMORY W. WORTHINGTON.
